(57) **CLAIM**

The ornamental design for a digital doorlock, as shown and described.

DESCRIPTION

FIG. 1 is a perspective view of a digital doorlock, showing my new design;

FIG. 2 is a front view of the digital doorlock;

FIG. 3 is a rear view of the digital doorlock;

FIG. 4 is a left side view of the digital doorlock;

FIG. 5 is a right side view of the digital doorlock;

FIG. 6 is a top plan view of the digital doorlock; and,

FIG. 7 is a bottom plan view of the digital doorlock.

In these drawings, the solid lines illustrate the claimed ornamental design, whereas the broken lines illustrate unclaimed environmental features and form no part of the claimed design.
